UNITED STATES PATENT OFFICE

168,772

CHAIR

Franz Wagner, Evanston, Ill., assignor to Arvin Industries, Inc., Columbus, Ind., a corporation of Indiana

Application September 27, 1952, Serial No. 21,612

Term of patent 14 years

(Cl. D15—8)

To all whom it may concern:

Be it known that I, Franz Wagner, a citizen of the United States, residing at Evanston, Cook County, Illinois, have invented a new, original, and ornamental Design for a Chair, of which the following is a specification, reference being had to the accompanying drawing, forming a part hereof.

Fig. 1 is a front perspective view of a chair, showing my new design.

Fig. 2 is a rear perspective view of the chair.

I claim:

The ornamental design for a chair, as shown.

FRANZ WAGNER.
